UNITED STATES PATENT OFFICE.

JAMES W. MILLER, OF JOHNSON CITY, TENNESSEE.

DESIGN FOR JOINT-RAKER.

46,406.

Specification for Design.

Patented Sept. 15, 1914.

Application filed July 8, 1914. Serial No. 849,856. Term of patent 14 years.

To all whom it may concern:

Be it known that I, **JAMES W. MILLER**, a citizen of the United States, residing at Johnson City, in the county of Washington and State of Tennessee, have invented a new, original, and ornamental Design for Joint-Rakers, of which the following is a specification, reference being had to the accompanying drawing, forming part thereof.

The figure is a perspective view of a joint raker, showing my design.

I claim:

The ornamental design for a joint raker, substantially as shown.

JAMES W. MILLER.

Witnesses:

E. B. HENSLEY,

R. H. MENDISH.
